(57) **CLAIM**

The ornamental design for a four wheel electric vehicle, as shown and described.

DESCRIPTION

FIG. 1 is a front elevational view of a four wheel electric vehicle, showing my design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a front right perspective view thereof; and,

FIG. 7 is a rear right perspective view thereof.

The bottom of the four wheel electric vehicle is not seen during ordinary use and forms no part of the claimed design. The broken line showing of parts of the drawings is included for the purpose of illustrating portions of the four wheel electric vehicle and forms no part of the claimed design.
